UNITED STATES PATENT OFFICE

2,419,359

FIRE ESCAPE

Henry Richard Harms Ludelfs, Grosse Pointe Woods, Mich.

Substituted for abandoned application Serial No. 379,503, February 18, 1941. This application October 28, 1946, Serial No. 706,143

1 Claim. (Cl. 227—33)

1

This invention relates to fire equipment and more particularly the fire escape set forth in my former application Serial No. 379,503, filed February 18, 1941.

The primary object of this invention resides in the provision of a fire escape adapted to be raised from the ground to windows in buildings so as to assist trapped individuals to safely escape.

Another object of this invention resides in the particular means for raising and lowering the cage.

A further object of this invention resides in the particular means for holding the cage from the walls of buildings.

A still further object of this invention resides in the particular association of the bag with the frame.

Aside from the aforesaid objects is the particular manner of disposing the pulleys on the frame.

With these and other objects in view this invention resides in certain novel features of construction and arrangement of elements to be hereinafter more particularly set forth in the specification, illustrated in the accompanying drawings and pointed out in the appended claim and, while this disclosure depicts my present conception of the invention, the right is reserved to resort to such changes in construction and arrangement of elements as come within the scope of the claim.

In the accompanying drawings forming a part of this application;

Fig. 1 is a front view of a portion of a building showing the fire escape raised to one window thereof.

Fig. 2 is a vertical sectional view thereof approximately on line 2—2 of Fig. 1.

Fig. 3 is an enlarged plan view of the frame with the cage removed.

Fig. 4 is a front view of the same showing the cage attached thereto.

Fig. 5 is an enlarged vertical sectional view approximately on line 5—5 of Fig. 2.

Fig. 6 is an end view of the cross-bar showing a link and cable attached thereto.

Fig. 7 is a front view thereof.

Fig. 8 is an enlarged detail sectional view approximately on line 8—8 of Fig. 2.

In the present illustration of this invention the letter A designates a portion of a residence or building showing a window B therein from which is adjustably suspended as by ropes or cables 5 anchored therein by a cross-bar 6, a fire escape

2

7 in the form of a perpendicularly movable cage or basket.

The fire escape 7 preferably consists of a frame 8 consisting of substantially rectangular angle-iron upper and lower members 9 and 10 connected at the medial portions of their sides by plates 11 and strengthened throughout by braces 12.

Projecting inwardly and upwardly from the upper end of the frame 8 are arms 13 strengthened by braces 14, said arms being adapted to rest against the center side wall of the building to hold the frame in spaced relation relative thereto.

Secured to the lower member 10 as by plates 15 11 and fastening elements 15 is a bag or cage 16 formed of any suitable material adapted to close the lower side of the frame and retain individuals entering the fire escape therein.

Projecting laterally from the plates 11 adjacent the upper member 9 are fork-shape lugs 17 having threaded inner ends 18 passing through the plates and connected to a cross-rod 19 by elongated nuts 20, said fork-shape lugs are adapted to pivotally support swivelled pulleys 21.

25 Formed on the arms 13 adjacent their inner ends are laterally extending lugs 22 adapted to pivotally support swivelled pulley 23 preferably disposed in perpendicular alignment with the pulley 21.

30 Slidably disposed on the cross-bar 6 are links 24 having apertures 25 in their free ends to receive the inner ends of cables 5 which are looped and fastened thereto in any suitable manner, said cables extend from the links and are trained 35 through the aligned pulleys 21 and 23 on opposite sides of the frame and are of sufficient length to raise and lower the fire escape from the ground to windows in buildings, it being apparent the length of the cables will be determined by the 40 height of the tallest buildings in the cities wherein the fire escapes are to be used.

In order to lighten the links on the cross-bar, suitable fastening elements 26 are associated therewith.

45 With a fire escape constructed in accordance with this invention it is simply necessary for the fireman to take the cross-bar with the cables attached thereto up a ladder and dispose it across a window wherein individuals are awaiting assistance whereupon firemen or individuals on the ground cause the cage to rise by walking in opposite directions with the free or lower ends of the cable taut or by standing at points on opposite sides of the fire escape and tightening the cables, elevation of the fire escape being caused

by the tendency of the cables to straighten out between the points of connection to the cross-bar and individuals pulling on the same.

Subsequent to occupancy of the fire escape by fire trapped individuals the cables are slackened to permit it to smoothly gravitate.

Due to the simplicity in construction of the present fire escape it is apparent operation thereof is performed without practice or skill and the cost of manufacture of the same will permit it to be sold at a reasonable price.

Having thus described my invention, what I claim and desire to protect by Letters Patent is:

A fire escape of the character described comprising a substantially rectangular frame, inwardly and upwardly extending arms secured to the top of the frame, a cage suspended from the bottom of the frame, a swivel pulley secured to each free end of the arms, a swivel pulley secured to each side of the frame remote from the pulleys on the arms, a cross-bar disposed across a window, links secured to the cross-bar, a cable connected to each link and trained

through aligned pulleys on the sides of the frame and arms and a cross-bar connecting the pulleys on opposite sides of the frame.

5 HENRY RICHARD HARMS LUDELFS.
